UNITED STATES PATENT OFFICE.

GUY V. HIATT, OF ATTICA, INDIANA.

COMBINATION SHADE AND CURTAIN HANGER.

1,275,423.

Specification of Letters Patent. Patented Aug. 13, 1918.

Application filed February 25, 1916. Serial No. 80,449.

To all whom it may concern:

Be it known that I, GUY V. HIATT, a citizen of the United States, residing at Attica, in the county of Fountain and State 5 of Indiana, have invented certain new and useful Improvements in Combination Shade and Curtain Hangers; and I do hereby declare the following to be a full, clear, and exact description of the invention, such as 10 will enable others skilled in the art to which it appertains to make and use the same.

The invention relates to improvements in shade and curtain hangers.

The object of the present invention is to 15 improve the construction of shade and curtain hangers and to provide a simple, practical, and comparatively inexpensive construction designed for hanging shades and curtains at windows and capable of ready 20 adjustment to adapt itself to shades of different widths and windows of different sizes.

A further object of the invention is to 25 provide a combination shade and curtain hanger of this character capable of being securely fastened to a window without the employment of nails, screws or similar fastening devices and capable of being readily removed and replaced without defacing or otherwise injuring wood-work.

With these and other objects in view the invention consists in the construction and 30 novel combination and arrangement of parts hereinafter fully described, illustrated in the accompanying drawings and pointed out in the claims hereto appended, it being understood that various changes in the form, proportion and minor details of construction may be resorted to without departing 35 from the spirit or sacrificing any of the advantages of the invention.

In the drawings

Figure 1 is a perspective view of a combined curtain and shade hanger constructed 40 in accordance with this invention,

Fig. 2 is an end elevation of the same,

Fig. 3 is a plan view,

Fig. 4 is a vertical sectional view on the line 4-4 of Fig. 3,

Fig. 5, is a detail perspective view of the shade supporting and curtain supporting bracket,

Fig. 6 is a detail view illustrating the construction for connecting the ends of the coiled curtain supporting springs with the arms of the curtain supporting brackets.

Like numerals of reference designate cor-

responding parts in the several figures of the drawings.

In the accompanying drawings the combination lace curtain and window shade hanger comprises in its construction spaced shade supporting brackets 1 and curtain supporting brackets 2 slidably and adjustably connected with the shade supporting brackets as hereinafter fully described. While the term lace curtain is employed in the specification it will be understood that various other analogous draperies may be substituted for lace curtains. Each shade 60 supporting bracket is designed to be constructed of suitable sheet metal or other material and it comprises a vertical body portion 3, a rearwardly extending top engaging arm 4 and a forwardly or outwardly 65 engaging arm 5.

The body portion 3 which may be finished in any suitable manner is preferably provided at its inner face with a tab 6 of suitable material to prevent it from marring 80 the face of a window frame or casing and the arm 4 which is adapted to extend over the upper edge of the window frame or casing 7 is provided with depending spurs or teeth 8 which are adapted to be embedded 85 in the said frame or casing 7. The outwardly extending supporting arms 5 are provided with a bearing opening 9 and a recess 10 for the reception of the journal 11 and the rod of the spring actuated roller 13 90 of a window shade 14. The rod 13 is connected with the spring, not shown, of the shade roller in the usual manner and the window shade is supported between the arms 5 as will be readily understood and it may 95 be quickly placed in and removed therefrom.

The shade supporting bracket 1 is also provided at its body portion with spaced integral upper and lower guiding lugs 15 formed by partially severing the metal of 100 the body portion 3 and curving the same to form guiding recesses for the curtain supporting brackets.

Each curtain clamping and supporting bracket 2 is preferably constructed of a single piece of stout wire or other suitable material which is bent to form a longitudinal loop 16 composed of upper and lower sides 17 and 18 and a connecting inner end portion 19. The upper and lower horizontal 105 side portions 17 are arranged in the recesses of the guiding lugs and are slideable longitudinally therein to permit the shade supporting bracket to be arranged at the de-

sired point and to enable a pair of hooks 20 and 21 to be engaged in the side edge of the window frame or casing. The wire of the curtain supporting bracket is extended 5 and bent at right angles at the outer end of the upper side 17 and is doubled to form a supporting arm 22, the free terminal portion of the wire at the inner end of the supporting arm 22 being bent to form the hook 20. The wire at the outer end of the other side 18 of the horizontal loop is bent rearwardly and then inwardly to form the hook 21. The sides of the supporting arm 22 are spread slightly at the outer end of the arm 15 to form an opening 23 for the reception of the shank 24 of a hook 25 provided at its outer end with an enlarged ornamental head 26 and engaging with its bill a loop 27 of a coiled spring 28. The enlarged head 26 is preferably in the form of an ornamental ball and the hook which is passed through the opening of the supporting arm 22 from the exterior thereof is engaged with the coiled spring 28 which is adapted to support 25 a lace curtain 29 or other suitable drapery. The lace curtain which may be composed of two sides or portions, as shown, is provided at the top with a hem or casing 30 through which the coiled spring passes and the said coiled spring is adapted to hold the hooks in engagement with the sides of the window frame or casing whereby the curtain and shade hanger is held to the window as firmly as if bolts, screws, or other fastening devices were employed and it is also adapted to be readily removed from the window and replaced as often as required without injuring or marring the wood-work. In applying the device to a window the 40 shade supporting brackets are arranged the proper distance apart on the window and are embedded therein. The curtain supporting brackets are then moved inwardly into engagement with the window frame or casing, the bills or engaging portions of the hooks 20 and 21 being preferably tapered as shown in Fig. 5 to provide spurs or prongs to enable them to be readily embedded in the wood-work. When the device 45 is removed it can be replaced in the same indentations or perforations previously engaged by the spurs 8 and the hooks 20 and 21.

Copies of this patent may be obtained for five cents each, by addressing the "Commissioner of Patents, Washington, D. C."

The coiled spring constitutes an extensible support for the curtain and also serves 55 to maintain the curtain supporting bracket in firm engagement with the window frame or casing. The sides of the longitudinal loop 16 are located above and below the supporting arm 5 which is provided in its upper 60 and lower edges with recesses 31 which are arranged in alignment with the recesses formed by the guiding lugs 15. By this construction, the loop 16 is guided at spaced points and the sides of the loop are maintained in engagement with the guiding lugs without the necessity of connecting the outer ends of the sides and relatively light material may be employed in the construction of the curtain supporting bracket. 70

What is claimed is:—

1. A combined shade and curtain support comprising a vertical body, a horizontally disposed attaching arm formed integrally with one end of the body, a shade supporting arm formed integral with one side edge of the body, said body provided with a pair of spaced lugs bent to provide bearings, and a curtain rod support including spaced arms slidably mounted in the bearing lugs and 75 engaging the upper and lower edges of the shade supporting arm, as and for the purpose specified.

2. A combined shade and curtain bracket comprising a vertical body, fabric strips secured to one face of the body, bearing lugs struck from the face of the body, an attaching arm at one end of the body, a shade supporting arm formed integrally with one side edge of the body and provided with 90 recesses in its upper and lower edges aligning with the bearing lugs, and a curtain pole support including spaced horizontally disposed arms adapted to be slidably and adjustably mounted in the bearing lugs and 95 recesses of the shade arm, said recesses in the shade supporting arm preventing the curtain pole supports from having lateral movement with relation to the body.

In testimony whereof I affix my signature 100 in presence of two witnesses.

GUY V. HIATT.
